CLAIM

The ornamental design for a advanced mulcher tooth assembly, as shown and described.

DESCRIPTION

FIG. 1 is a front perspective view of a advanced mulcher tooth assembly constructed in accordance with a preferred embodiment.

FIG. 2 is a rear perspective view of the advanced mulcher tooth assembly.

FIG. 3 is a left side view of the advanced mulcher tooth assembly.

FIG. 4 is a right side view of the advanced mulcher tooth assembly.

FIG. 5 is a rear end view of the advanced mulcher tooth assembly.

FIG. 6 is a top view of the advanced mulcher tooth assembly.

FIG. 7 is a bottom view of the advanced mulcher tooth assembly.

FIG. 8 is an exploded view of the two components of the advanced mulcher tooth assembly; and,

FIG. 9 is a perspective view of the advanced mulcher tooth assembly installed on a rotating drum shown in broken lines that forms no part of the claimed design.
